HYDRAULIC SYSTEM

Fritz Freundel and Heinrich Rosenthal, Dessau, Germany, assignors to Junkers Flugzeug-und-Motorenwerke Aktiengesellschaft, Dessau, Germany, a corporation of Germany

Application June 27, 1940, Serial No. 342,612
In Germany March 7, 1939

11 Claims. (Cl. 60—97)

This invention relates to improvements in hydraulic systems, and refers to such systems, equipped with volume distributors, wherein means are provided for insuring that a plurality of pistons, each mounted in a cylinder, are moved, substantially uniformly and simultaneously, completely to the ends of their strokes.

In most hydraulic systems of this general nature, due to structural inaccuracies or for other reasons, it often happens that the pistons do not move together and some, or one, of them never completes its stroke and reaches its end position. This even occurs when volume distributors are employed due to the fact that they may not distribute the flow with sufficient accuracy. The main disadvantage of not moving the pistons simultaneously and uniformly when a volume distributor is used is that, in conventional layouts including a parallel flow to the cylinders, when the first piston reaches its end position and stops the entire flow to the cylinders ceases, and therefore the other piston, or pistons, cannot be moved to their predetermined end positions where, in many cases, piston locking means are provided to engage them. And even where automatic valves are employed for shutting off the flow to a cylinder in which the piston has reached its end position this same undesired result often occurs.

It is an object of this invention to provide hydraulic systems for use when volume distributors are used for dividing the flow substantially equally in a plurality of directions to actuate a plurality of pistons, or other movable parts, including a releasing means for the liquid flowing in each direction so that after one piston has been moved to the end of its stroke its releasing means functions and permits a parallel flow to continue to all pistons so that the other pistons may still be moved to their predetermined end positions. For, as previously stated, with these volume distributors, as soon as the flow in any one direction therefrom stops the entire parallel flow through the distributor stops. Moreover these releasing means consist of relief valves which may be placed at different locations in the systems, even in the pistons themselves which are moved by the pressure flow if so desired.

This invention contemplates several detailed structural variations in all of which the same underlying principle occurs: Namely that a parallel flow through all the feed lines occurs, and is maintained even after the fastest moving piston has reached the end of its stroke so that the

other pistons may also be brought to their respective end positions; this, obviously, is necessary when a volume distributor is employed for the reason already noted above.

Some of the modified structural embodiments herein contemplated include: An arrangement having a relief valve in each feed line from the distributor set to open at a pressure slightly in excess of normal working pressure to permit the flow from that feed line to pass through a free return to a reservoir after the piston moved thereby has reached its predetermined end position, thus permitting a flow to continue to the other and slower moving piston, or pistons. An arrangement including relief valves arranged between the feed lines so that when one piston reaches the end of its stroke the flow from the feed line operating that piston then passes into the other feed line to augment the flow therethrough. Another arrangement wherein a common relief valve is connected to two feed lines so that the flow through either line, after the piston actuated thereby has reached its end position, passes through a free return and to a reservoir. Yet another arrangement includes electrical means operated by either piston as it reaches its end position and opens a relief valve in the feed line to that piston to permit a flow to continue through that line by-passing it back to the reservoir.

The various embodiments above referred to are hereinafter more fully described with the aid of the accompanying drawings, wherein:

Figure 1 illustrates a diagrammatic view of a hydraulic system including separate relief valves in the feed lines each connected to a free return to a reservoir.

Figure 2 shows diagrammatically a modified system wherein the feed lines are connected to one another by relief valves.

Figure 3 is a further modification wherein a relief valve common to two feed lines is connected by a free return to a reservoir, and

Figure 4 shows another modification wherein relief valves in the feed lines are electrically operated.

Referring to the drawings, 1 and 2 are cylinders having pistons 3 and 4 therein from which operating rods 5 and 6 respectively project, and which are primarily intended to operate mechanism such as landing gears on airplanes. Connected to the reservoir 1 by a suction line 1a is a pump 8 which discharges liquid under pressure through a delivery line 11 to a conventional three-way control valve 9 having outlet connec-

tions *a*, *b* and *c* through any one of which the flow may be discharged as desired. The connections *a* and *c* (the latter terminating in a pipe *17*) are connected to volume distributors *10* and *31* respectively of known construction, which may be of the type illustrated and described in the patent to Klein 2,242,002, May 13, 1941. The distributor *10* divides the flow equally into the feed lines *12*, *14* and *13*, *15*; and the distributor *31* equally divides the flow through the feed lines *18* and *19*. The feed lines *14*, *19*, *15* and *18* are connected to the extremities *1''* and *1'*, and *2''* and *2'* of the cylinders *1* and *2* respectively. The control valve connection *b* terminates in a free return line *16* to the reservoir *1*, and the discharge side of the pump *8* is also connected to the return line *16* through a safety valve *32* which limits the pressure maintained in the system.

As the volume distributors *10* and *31* cannot always be relied upon to distribute the flow through the feed lines *14*, *19*, *15* and *18* with sufficient accuracy to insure both pistons reaching their predetermined end positions in their cylinders *1* and *2* at exactly the same time relief valves are provided to permit continued flow through the volume distributor and the feed lines fed through it after the first piston has reached its position at one extremity or the other of its cylinder.

In the arrangement shown in Figure 1, two relief valves *21* and *22* are employed which are connected to the feed lines *12*, *14* and *13*, *15* respectively. These relief valves are each also connected to the free return line *16* and are set to open at a pressure slightly in excess of the normal operating pressure in the system so that when either piston *3* or *4* reaches the outer extremity (*1'* or *2'*) of its travel an excess pressure is built up in the feed line, *14* or *15*, through which the flow occurred to move that piston. This excess pressure opens the relief valve, *21* or *22*, connected to that feed line so that a flow continues through that valve and the return line *16* back to the reservoir *1*, as well as through the other feed line to continue to move the piston which has not yet reached its end position. Thus a parallel flow continues for without it passage from the volume distributor to the piston which has not finished its stroke could not occur.

Similarly when the pistons *3* and *4* are being moved to the cylinder extremities *1''* and *2''* the flow passes through the volume distributor *31* and the feed lines *19* and *18* which have other relief valves *23* and *24* respectively connected thereto and are also suitably connected to the return line *16*. Thus by manipulation of the control valve *9* the flow may be directed to either volume distributor *10* or *31* (or directly to the return line *16* when the valve is neutrally positioned) to move the pistons *3* and *4* to either extremity of their strokes with the assurance that both pistons will reach their outer or inner cylinder extremities even if one piston does so somewhat in advance of the other. The numeral *20* denotes cases, or rectifying device containers, to house the separate sets of relief valves *21* and *22*, and *23* and *24*.

In the modification shown in Figure 2, the arrangement differs in that opposed relief valves *25* and *26* connecting the feed lines *12*, *14* and *13*, *15* are provided so that when further flow through one feed line is prevented because the piston actuated thereby has reached the end of its stroke flow from that feed line then passes through one of the relief valves into the other

feed line thus permitting continued movement of the other piston by combined flow through both feed lines *12*, *14* and *13*, *15* thereinto from the volume distributor *10*. Movement of the pistons in the reverse direction occurs similarly through the feed lines *19* and *18* which are similarly connected to one another by opposed relief valves housed within the case *20*.

In the modification shown in Figure 3 the pipes or feed lines *12* and *13* are connected to opposite ends of a cylinder *27* having a floating plunger *27a* therein. Centrally of its length this cylinder *27* is connected to a relief valve *28* which is also suitably connected to the return line *16*. Consequently excess pressure built up in either feed line *12*, *14* or *13*, *15* causes movement of the plunger *27a* so that the flow from that line may pass through the relief valve, after having moved the plunger *27a*, and through the return line *16* to the reservoir *1*. Within the case *20* a similar combination of a cylinder, as shown at *27*, having a plunger therein, and a relief valve, as shown at *28*, are also provided which are suitably connected to the feed lines *19* and *18* through which a flow occurs past the volume distributor *31* when the pistons *3* and *4* are being moved inwardly.

In the modification shown in Figure 4 relief valves *29* and *30* are provided in the feed lines *12*, *14* and *13*, *15* respectively through which a flow occurs to move the pistons *3* and *4* to the extremities *1'* and *2'* respectively of their cylinders. Both these relief valves *29* and *30* are again connected over the line *17* and three-way control valve *9* to the return line *16*, but in this instance these valves are electrically operated and controlled by solenoids *33* and *34* respectively which are energized by circuits closed by movement of the pistons *3* and *4*.

Mounted adjacent the cylinders *1* and *2* are longitudinally slidable members *47* and *48* having inwardly projecting extremities adapted to be engaged by trips *39* and *40* extending from the rods *5* and *6* respectively. Connected to the members *47* and *48* are leads *52* and *53* respectively which extend to opposite sides of a source of power *54*, and *41* indicates a switch in the lead *53*. Extending from the members *47* and *48* are contacts *47a* and *48a* which are electrically connected to the lines or leads *52* and *53* respectively. Spaced on opposite sides of each contact *47a* and *48a* are fixed contacts *35* and *35a*, and *36* and *36a* respectively. Extending from the contacts *35* and *35a* are leads *51* and *56* which are connected also to the solenoids *33* and *34* respectively, and extending from the contacts *36* and *36a* are other leads *50* and *55* which are also connected to the solenoids *33* and *34* respectively.

If the piston *4* is first moved to its outward position *2'* by a flow entering the cylinder *2* from the feed line *15* then the contact *48a* is moved into engagement with the contact *36a* by movement of the member *48* which is shifted by the trip *40*. Then a circuit is closed through the leads *53*, *55*, the solenoid *34*, and the leads *56* and *52* through the contacts *35a* and *47a*, because during the preceding movement of the piston *3* to the inner extremity, *1''*, of its stroke the contacts *47a* was moved into engagement with the contact *35a*. However as that piston is moved to the outer end of its travel the member *47* is moved by the trip *39* and that contact *47a* is brought into engagement with the contact *35* thereby breaking the circuit so that both relief valves are again closed. A similar solenoid operated arrangement

may also be provided for operating the relief valves housed in the case 20 and connected to the feed lines 19 and 18.

In Figure 1 yet another modified arrangement is shown also. The piston 4 is provided with opposed relief valves 37 and 38 extending therethrough, so that in the event the flow through the feed line 15 causes the piston 4 to reach the end 2' of its stroke before the piston 3 reaches its stroke extremity 1' then that flow may continue through the valve 37 and escape through the pipe 18, the volume regulator 31 which is then not working, to the control valve 9 wherein the outlets b and c are then connected as the discharge from the pump 8 is being directed through the outlet a, and through the return line 16 to the reservoir 1. Or again the valve 38 is opened when the flow entering from the feed line 18 has moved the piston 4 first to the opposite end of its stroke, so that this flow may continue through that relief valve 38 and return similarly through the feed line 15.

While in the foregoing the preferred embodiments of the invention have been described and shown, it is understood that still other alterations and modifications may be made thereto provided they fall within the scope of the appended claims.

What we claim is:

1. A hydraulic system in combination with moving aircraft parts comprising a pumping unit, a plurality of cylinders having pistons therein, a volume distributor connected to the discharge side of the pumping unit, a plurality of feed lines extending in parallel from the distributor to the cylinders for the pressure flow passing therethrough to actuate the pistons therein, and pressure releasing means connected to the feed lines whereby a parallel flow is continued through all the latter after the piston in one cylinder has reached its limit of travel.

2. In a hydraulic system, the combination set forth in claim 1, wherein the pressure releasing means consists of opposed relief valves connecting the feed lines whereby the flow from the feed line to one cylinder, after the piston therein has reached its limit of movement, augments the flow in the other feed line.

3. In a hydraulic system, the combination set forth in claim 1, wherein the pressure releasing means consists of a relief valve connected to each feed line intermediately of its length.

4. In a hydraulic system, the combination set forth in claim 1, wherein the pressure releasing means consists of a relief valve connected to each feed line, and electrical means for operating each relief valve including a switch mechanism actuated by movement of each piston as it reaches the end of its stroke.

5. In a hydraulic system, the combination set forth in claim 1, wherein the pressure releasing means consisting of a centrally apertured cylinder connected at each extremity to one of the feed lines, a plunger in the cylinder normally closing the aperture, and a relief valve connected to the cylinder aperture whereby either feed line may be connected to the relief valve by movement of the plunger.

6. In a hydraulic system, the combination of a

reservoir, a pumping unit having its suction side connected thereto, a volume distributor connected to the discharge side of the pumping unit, a plurality of cylinders having pistons therein, a separate feed line from the distributor to each cylinder, a return line connected to the reservoir, and pressure releasing means connected to said feed lines and said return line whereby the flow through any feed line is by-passed through the return line to the reservoir when the flow through that feed line stops due to the piston actuated by that flow having reached its limit of travel in its cylinder.

7. In a hydraulic system, the combination set forth in claim 6, including a pipe having a safety valve therein extending from the discharge line between the pump and the volume distributor to the return line to limit the pressure of liquid passing through the volume distributor, either pressure releasing means being adapted to be opened by excess pressure in its feed line caused by resistance offered by the piston in the cylinder connected to that feed line after said piston has completed its stroke.

8. A hydraulic system for use in combination with moving aircraft parts comprising a pumping unit, a plurality of cylinders having pistons therein, a volume distributor connected to the discharge side of the pumping unit, a plurality of feed lines extending in parallel from the distributor to the cylinders, and pressure releasing means connected to the feed lines at points removed from the cylinders whereby a parallel flow is continued through said lines after a piston in one cylinder becomes stationary at any point throughout its limit of travel.

9. A hydraulic system for use in combination with pairs of aircraft parts adapted to move in unison throughout equal distances of travel comprising a pumping unit, a plurality of cylinders having pistons therein, a volume distributor connected to the discharge side of the pumping unit, a plurality of feed lines extending in parallel from the distributor to the cylinders, and pressure releasing means connected to the feed lines, said pressure releasing means being set to operate at a pressure exceeding that normally required to operate the pistons and so arranged in each path of fluid travel as to permit continued flow through the parallel feed lines when either piston meets undue resistance to travel in its cylinder.

10. The arrangement set forth in claim 9 wherein the pressure releasing means comprises opposed relief valves connecting the feed lines whereby the flow from the feed line to one cylinder augments the flow in the other feed line after the piston in said first-mentioned cylinder has reached its limit of travel.

11. The arrangement set forth in claim 9 wherein the pressure releasing means comprises a centrally apertured cylinder connected at each end to one of the feed lines, a plunger in the cylinder normally closing the aperture, and a relief valve connected to the cylinder aperture whereby either feed line may be connected to the relief valve by movement of the plunger.

FRITZ FREUNDEL.
HEINRICH ROSENTHAL.
